UNITED STATES PATENT OFFICE.

ANDREW HULLINGER, OF BOLIVAR, OHIO.

WRENCH.

SPECIFICATION forming part of Letters Patent No. 469,701, dated March 1, 1892.

Application filed April 16, 1891. Serial No. 389,214. (No model.)

To all whom it may concern:

Be it known that I, ANDREW HULLINGER, a citizen of the United States, residing at Bolivar, in the county of Tuscarawas and State 5 of Ohio, have invented a new and useful Wrench, of which the following is a specification.

This invention relates to improvements in ratchet-wrenches, the objects in view being to 10 provide a wrench of cheap and simple construction adapted to operate upon nuts of various sizes and shapes to be provided with means for adapting the wrench for both applying and removing nuts or converting the 15 wrench into a rigid wrench.

Other objects and advantages of the invention will appear in the following description, and the novel features thereof will be particularly pointed out in the claims.

Referring to the drawings, Figure 1 is a top 20 plan view of a wrench constructed in accordance with my invention. Fig. 2 is a vertical longitudinal section. Fig. 3 is a transverse section on line x of Fig. 1. Fig. 4 is a detail in perspective of the socket-locking key. Fig. 5 is a detail in perspective of the removable nut-receiving socket, the same being inverted. Fig. 6 is a detail in perspective of the pawl-shifting lever.

Like numerals of reference indicate like 30 parts in all the figures of the drawings.

In practicing my invention I construct a stock which consists of a handle 1 of suitable length, and a head 2, the same being cylindrical in plan, considerably thicker than the handle and provided with a circular recess or opening 3, having formed upon its under side an internal annular bearing-flange 4. The bearing-flange 4 loosely receives the cylindrical hub 6 of a ratchet-wheel 7, the ratchet-wheel occupying that portion of the circular recess unoccupied by the flange. To the opposite sides of the hub are secured by bolts 6^a a pair of circular plates 7^a, which 45 plates are slightly greater in diameter than the ratchet-wheel and agree in diameter with the head of the wrench, so that by means of the plates the ratchet-wheel is prevented from displacement, and is permitted to readily rotate within the head.

The hub and plates are provided with cor-

responding rectangular openings 8, which receive the similarly-formed socket 9. A series of these sockets 9 is employed, if desired, and may be provided with plain or tapered openings for the reception of different sizes of nuts. The socket is also provided upon its under side with a projecting flange or lip 10, and the same takes into a corresponding recess formed in one of the plates. The opposite end of the socket has two of its corners grooved or notched, as at 11, and receives a key 12.

As shown in Fig. 4, the key consists of a blank of spring-wire doubled upon itself and curved to form a handle 13, beyond which the terminals of the key diverge, and are inwardly bent, forming spring locking-arms 14, adapted to be sprung into engagement with the grooves 11 at the corners of the sockets. 70 When the key is in position, the same prevents the withdrawal of the socket from the hole in the hub of the ratchet-wheel in one direction, while the flange upon the opposite end of the socket prevents the withdrawal of the same in the opposite direction. It will be observed that the key may be readily withdrawn from its locking engagement with the socket and the same readily removed and replaced by others. At the juncture of the 75 head of the wrench with the stock or handle opposite recesses 16, opening into the head, are provided, and in each of said recesses there is pivoted at 17 a pawl 18, the outer ends of the pawls being inwardly disposed and adapted to engage with the teeth of the ratchet-wheel. To insure engagement, light springs 19 are interposed between the tails of the pawls and the stock or handle. To the 80 handle is pivoted, as at 20, a shifting-lever, and the same consists of a handle 21, extending along the handle or stock of the wrench, and at its front end is a pair of oppositely-disposed bent shifting-arms 22, the ends of which rest upon the outer ends of the pawls 85 and are a distance apart slightly greater than the width of the stock or handle of the wrench. A pin 23 projects from the handle of the wrench, slightly in rear of and in line with the pivot of the shifting-lever, and by throwing the handle of said lever to the right or left of said pin, in which positions it will be 90 95 100

consequently held, the right or left pawl will be thrown into engagement, while its companion will be pressed at its rear end and withdrawn from engagement. By placing the handle of the shifting-lever directly over the pin the terminals of said lever do not operate either of the pawls, so that both are thrown into engagement, and hence I form a rigid socket-wrench.

- 10 From the foregoing description it will be seen that I provide a simple economic construction of wrench adapted to be used upon various-sized nuts and to be operated either in applying or removing the same in obscure 15 or intricate positions, said wrench requiring but a small space in which to operate, and that I have provided a simple device readily accessible to the operator, by which either or both of the pawls may be thrown into engagement or either withdrawn.

Having described my invention, what I claim is—

1. In a wrench, the combination, with the stock or handle terminating at its front end 25 in a circular head or ring provided near one side with an internal annular flange, a hub mounted for revolving in the flange and provided above the same with a ratchet-wheel, and opposite circular plates secured to the hub 30 and overlapping the faces of the head of the wrench, of a rectangular socket removably inserted in a correspondingly-shaped opening formed in the hub, said socket being provided

with a flange at one end taking into a recess formed in one of the plates and at its opposite end provided at diagonally-opposite corners with grooves, and the locking-key formed of spring-wire and consisting of a handle and diverging terminals inwardly bent at their ends and sprung removably into position in the grooves, substantially as specified.

2. In a wrench, the combination, with the handle terminating at one end in a circular head or ring, a ratchet-wheel mounted for rotation in said ring, and means for securing 45 the same, of a pair of pawls pivoted in recesses formed at the juncture of the ring and handle, the forward ends of the pawls being inwardly disposed to engage with the teeth of the ratchet, springs interposed between the 50 tails of the pawls and the bottoms of the recesses, a T-shaped lever pivoted upon the handle and having its opposite branches depending to bear upon said pawls, and a locking-pin projecting from the handle in rear of 55 the pivot of the lever and to either side of which said lever is adapted to be thrown, substantially as specified.

In testimony that I claim the foregoing as my own I have hereto affixed my signature in presence of two witnesses.

ANDREW HULLINGER.
